Primary Examiner — Darcey E Gottschalk*Assistant Examiner* — Bailey M Knotts(74) *Attorney, Agent, or Firm* — Cook Alex Ltd.(57) **CLAIM**

The ornamental design for a pendant as shown and described.

DESCRIPTION

FIG. 1 is a perspective view of a pendant;

FIG. 2 is a front elevational view of the pendant;

FIG. 3 is a rear elevational view of the pendant;

FIG. 4 is a left side elevational view of the pendant;

FIG. 5 is a right side elevational view of the pendant;

FIG. 6 is a top plan view of the pendant; and,

FIG. 7 is a bottom plan view of the pendant.

The broken line portions of the drawings are included to show portions of the article that form no part of the claimed design and represent environmental structure only.

1 Claim, 4 Drawing Sheets(56)
